(57) **CLAIM**

The ornamental design for a writing instrument, as shown and described.

DESCRIPTION

FIG. 1 is a right front perspective view of a writing instrument showing my new design;

FIG. 2 is a left front perspective view thereof;

FIG. 3 is a front elevational view thereof;

FIG. 4 is a rear elevational view thereof;

FIG. 5 is a right elevational view thereof;

FIG. 6 is a left elevational view thereof;

FIG. 7 is a front elevational view of the writing instrument showing the clip tab rotated;

FIG. 8 is a top plan view thereof; and,

FIG. 9 is a bottom plan view thereof.

The broken lines in the figures show portions of the writing instrument that form no part of the claimed design.

1 Claim, 4 Drawing Sheets
